DESIGN FOR A BRAID

Morris J. Gornstein, New York, N. Y.

Application January 14, 1941, Serial No. 93,038

Term of patent 3½ years

To all whom it may concern:

Be it known that I, Morris J. Gornstein, a citizen of the United States and resident of New York city, in the county of New York and State of New York, have invented a new, original, and ornamental Design for a Braid, of which the following is a specification, reference being had to the accompanying drawing, forming a part thereof.

The figure of the drawing is a face view of the braid, showing my new design.

I claim:

The ornamental design for a braid, as shown.
MORRIS J. GORNSTEIN.
